UNITED STATES PATENT OFFICE.

JOHN PETERSON, OF MINNEAPOLIS, MINNESOTA.

STORM-SASH.

1,368,450.

Specification of Letters Patent. Patented Feb. 15, 1921.

Application filed December 26, 1916. Serial No. 138,708.

To all whom it may concern:

Be it known that I, JOHN PETERSON, a citizen of the Kingdom of Sweden, resident of Minneapolis, county of Hennepin, State 5 of Minnesota, have invented certain new and useful Improvements in Storm-Sashes, of which the following is a specification.

The object of my invention is to provide a storm sash of such construction that a 10 section or light of the glass therein may be moved to admit or exclude air without moving the frame or rails in which the glass is mounted.

A further object is to provide a storm sash 15 of such construction that a glass or light of the glass can be removed entirely and a screen substituted therefor, so that the sash may remain in the window during the summer months and one portion of it serve as a 20 window screen.

Other objects of the invention will appear from the following detailed description.

The invention consists generally in various constructions and combinations, all as hereinafter described and particularly pointed 25 out in the claims.

In the accompanying drawings forming part of this specification,

Figure 1 is a vertical sectional view 30 through a window frame, illustrating the preferred manner of mounting my storm sash therein,

Fig. 2 is a vertical sectional view, taken on a line at right angles substantially to the 35 section line of Fig. 1,

Fig. 3 is a horizontal sectional view, showing the manner of mounting the movable light or pane in the sash,

Fig. 4 is a vertical sectional view, through 40 the movable section of the glass,

Fig. 5 is a view partially in section, showing the movable section of the sash removed from the window.

Fig. 6 is a view of the screen section that 45 is substituted for the light of glass to adapt the window for summer use,

Fig. 7 is a sectional view on the lines 7—7 of Fig. 5.

In the drawing, 2 represents a window 50 frame and 3 the ledge formed on the outer portion of the frame to provide a seat 4 for the storm sash 5, which is inserted into the window from the inside of the building. 6 represents the lower sash, 7 the upper sash 55 of the window and 8 the window sill. These

may be of any ordinary or preferred construction, which will permit the storm sash to be placed in the window from the inside. The sash is held in place by suitable means, such as latches 9 fitting within recesses 10 in the jamb of the window. A storm sash mounted in this way obviously cannot be opened conveniently for admitting fresh air or for other purposes, and the object of my present invention is to so mount one section 60 or light of the storm sash that it can be easily moved to air the room or obtain access to the outside of the window.

Mounted in the storm sash are vertically arranged guides 11 and 12, consisting preferably of flat plates projecting into the opening in the window sash. One of these plates extends to the top of the sash, while the other terminates at a point near the middle thereof to allow the convenient removal of 65 the sliding frame therefrom, as will herein-after appear. This sliding frame comprises upper and lower rails 13 and 14 and side rails 15.

The upper and lower rails have forward 70 portions, U-shaped, substantially, in cross section, into which the upper and lower edges of the light of glass 16 are inserted and the ends of the side rails are inserted into the end portions of the top and bottom 75 rails and secured thereto by suitable means, such as bolts 17. These bolts are removable for the purpose of separating the rails of the frame and removing the glass in case of breakage or for any other reason. The 80 top rail also has a looped rearwardly extending portion 18 provided with a packing strip 19 of felt, or other suitable material, which forms a yielding seat for the upwardly turned edge 20 of a plate 21 that 85 is mounted on the window transom 22, the felt strip closing the joint between the rail and the transom and preventing the entrance of cold air at this point.

The lower rail of the frame has a part 100 23 to receive a rib 24 on the sash and separated therefrom by a suitable packing 25. The side rails have looped extensions 26 to receive the plates 11 and 12 and also have packing strips 27, the plates 11 and 12 serving as vertical guides for the frame when it is raised or lowered. One of the rails is preferably provided with a series of lugs 26' and a latch 27' is mounted on 105 the sash in position to be swung into the 110

path of one of the lugs for the purpose of holding the sliding frame at different elevations. A hook 28 is preferably provided for locking the frame in its closed 5 position.

It is my intention to allow this storm sash to remain in the window during the summer months and to adapt the sash for a half screen I provide a frame 29 in which 10 a suitable screen 30 is mounted, said frame being substantially the size of the frame for the light of glass 16 and adapted to be substituted therefor when it is desired to convert the storm sash into a screen. The 15 screen frame will be raised and lowered in the sash in substantially the same manner as previously described with reference to the sash with the light of glass.

The device may be applied to windows 20 of different sizes and shapes and in various ways the details of construction herein shown and described may be modified and still be within the scope of my invention.

I claim as my invention:

25 1. The combination with a storm sash having a centrally disposed transom, a closure for the space above said transom, and vertical guide plates mounted in the sash stiles, one of said plates terminating with 30 the transom and the other extending to the top of the sash, of a sliding closure frame comprising upper and lower and side rails secured together, the side rails being formed on one face with outwardly turned looped

portions disposed to receive the vertically 35 disposed guide plates.

2. The combination with a storm sash having a centrally disposed transverse transom and a fixed light of glass above the transom, of a vertically slidable frame below the transom and composed of top and bottom and side rails substantially U-shaped in cross-section to receive the edges of a closure member for the frame, the adjacent ends of the rails telescoping one in 45 the other at the corners of the frame, and separable fastening means for securing the rails together at their adjacent ends.

3. The combination with a storm sash having a centrally disposed transverse transom, a fixed light of glass above the transom, a plate secured to the transom and projecting inwardly and upwardly, and an upwardly extending ledge on the bottom rail of the sash, of a vertically slidable 55 frame normally below the transom and composed of top and bottom and side rails and containing a closure member, the top and bottom rails being formed with inverted U-shaped members disposed to receive the upwardly projecting plate on the transom and the upwardly extending ledge respectively when the slidable frame is in its lowermost position.

In witness whereof, I have hereunto set 65 my hand this 18" day of December, 1916.

JOHN PETERSON.
